CLAIM

We claim the ornamental design for a barcode scanner, as shown and described.

DESCRIPTION

FIG. 1 is a perspective view of a barcode scanner showing our new design from the front, top, and left side; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; and, FIG. 7 is a bottom plan view thereof.
The broken lines are directed to features of the barcode scanner that form no part of the claimed design.

1 Claim, 7 Drawing Sheets
